US00D737321S

(12) United States Design Patent
Lee

(10) Patent No.: US D737,321 S
(45) Date of Patent:  Aug. 25, 2015

(54) DISPLAY SCREEN OR PORTION THEREOF
WITH ICON

(71) Applicant: Samsung Electronics Co., Ltd.,
Suwon-si (KR)

(72) Inventor: Seung-Myung Lee, Seoul (KR)

(73) Assignee: Samsung Electronics Co., Ltd.,
Suwon-si (KR)

() Term: 14 Years

(21) Appl. No.: 29/456,255

(22) Filed: May 29, 2013

(30) Foreign Application Priority Data

Feb. 23, 2013 (KR) 30-2013-0009521
(51) LOC (10) Cl. 14-04

(57) CLAIM

The ornamental design for a display screen or portion thereof with icon, as shown and described.

DESCRIPTION

FIG. 1 is a front view of a display screen or portion thereof with icon, showing my new design; and,

FIG. 2 is a front view of a second embodiment thereof.

The broken line showing of the display screen or portion thereof is included for the purpose of illustrating portions of the article and forms no part of the claimed design.

The color of the display screen or portion thereof with icon, if any, forms no part of the claimed design; a display screen or portion thereof with icon according to the claimed design may be of any color or combination of colors.

1 Claim, 2 Drawing Sheets
